UNITED STATES PATENT OFFICE.

CARL WILLIAM EISENMANN, OF CHICAGO, ILLINOIS.

AUTOMATICALLY-OPERATED SWITCH.

1,106,372.

Specification of Letters Patent. Patented Aug. 11, 1914.

Application filed July 1, 1912. Serial No. 706,935.

To all whom it may concern:

Be it known that I, CARL W. EISENMANN, a subject of the German Empire, and resident of Chicago, in the county of Cook and State of Illinois, have invented certain new and useful Improvements in Automatically-Operated Switches, of which the following is a full, clear, and exact specification.

This invention relates to improvements in automatically operated switch systems for making and breaking the circuit between a dynamo and a storage battery, in electric systems generally, but more specifically for railway cars, in which the switch contacts are mounted on a movable member actuated by electro-magnets, and on the demagnetization of which magnets the gravity of the movable member, moves the switch to an open position, and is alone the sole means for maintaining the switch in its open position. In practice it is found that in the presence of the rough handling of trains or their leaving the rails, the force of this gravity of the lever is not sufficient to prevent the frequent accidental closing of the switch, which is also not infrequently closed by the unintentional physical contact of the train crew and others, with the lever, with the result that the dynamo being inactive or its voltage lower than the operative voltage of the battery, the latter is discharged or the fuse burned out, or connections fused and destroyed. In other words, whenever, or if under any circumstances the circuit between a dynamo and a storage battery is closed at a time when the voltage of the battery is greater than that of the dynamo, the battery will be discharged, the fuse burned out and possibly the whole lighting system will be put out of commission, and it is to prevent the accidental occurrence of this result to which my invention is directed.

The object of my invention broadly stated, is to provide a means, automatically operating, to prevent the closing of the switch between a storage battery and a dynamo, at any time when the voltage of the dynamo is less than that of the battery, and until the voltage of the dynamo is equal to or exceeds that of the operative voltage of the battery.

More specifically stated, the object of my invention is to provide an automatically electrically operated means which, in addition to the gravity of a movable support for the contacts of the switch for opening and closing the circuit between the battery and

a dynamo, furnishes to the said movable support a force maintaining the switch open in the presence of jars from a running train, its sudden stoppage and physical contact with the member which, otherwise, would move the contact to a position accidentally closing the circuit.

With these ends in view, my invention finds embodiment in certain features of novelty in the construction, combination and arrangement of parts, by which said objects and certain other objects are hereinafter attained, all as fully described with reference to the accompanying drawing, and more particularly pointed out in the claims.

Said drawing illustrates diagrammatically that portion of an electric lighting system to which my invention is adapted, and in which it finds embodiment.

Similar characters of reference indicate the same parts in the drawing.

2 indicates a battery of the construction and voltage commonly employed in railway cars and other electric light systems, which battery is connected with the positive side of lamps 3 by wire 4, a wire 5 connecting the battery with the negative side of said lamps, and the dynamo 6 through brush 7. The negative brush 7 of the dynamo is connected to the shunt dynamo field 8 by the wire 9; to the negative side of the battery by wire 5; and to the negative side of the lamp circuit 3 by wire 9. The switch 10—11 is obviously for the purpose of connecting and disconnecting the lamps from the dynamo and battery. The positive side of the dynamo is in circuit with one terminal of a coarse "retaining" winding 12, on the cores 13 and 14 of an electro-magnet by means of wire 15, the other terminal of this winding being connected by a wire 16 with a switch block 17. The dynamo is also in shunt circuit with the fine wire "lifting" coils 18 on the poles 13 and 14 of a magnet, by means of a wire 19 for one terminal, and 20 for the other terminal thereof.

Pivoted at one end to a fixed bracket 21 is a lever 22 on the opposite and free end of which are supported contact fingers 23 and 24 respectively opposite contact post 17, and contact post 25, the contact post 25 being connected with the positive side of the battery by wire 26, connected as it is shown with wire 4, contact post 17 being connected with the positive side of the dynamo by wire 16. The lever 22 is held in contact with the

magnet above referred to, and the switch closed so long as the voltage of the dynamo is equal to or above that of the operative voltage of the battery. When, however, the 5 voltage of the dynamo becomes less than that of the operative voltage of the battery, then the lever by gravity releases itself from the magnet, and thereby opens the switch, when, and so long as the voltage of the dynamo equals or is above the operative 10 voltage of the battery, the fine wire coils will be energized sufficiently to lift the lever to contact with the magnet when the subsequent force following the energizing of the coarse 15 wires will retain the lever to contact with the magnet and the switch closed. For the purposes above described, it should here be noted that there are more turns of the fine wires in the lifting coil than in the heavier 20 wires of the retaining coil of the magnet.

Every feature and operation of the structure so far described is old, and subject to the objection that with the lever out of contact with the magnets, and the switch open 25 there is no force, other than the gravity alone of the lever, to prevent jars transmitted from a moving train, or its sudden stopping or an inadvertent slightly lifting physical contact with the free end of the 30 lever from lifting the lever, sufficient to close the switch, and as a result discharge the battery and burn out the fuse, and thereby put the lamp or dynamo system, or both, out of commission, if and when at that time the 35 dynamo is inoperative or has lower voltage than the operating voltage of the battery. To overcome, and thereby entirely avoid so far as is possible with automatically operating means, this very serious objection in 40 operation from any of the causes above enumerated, my invention finds embodiment in the employment of a "holding" magnet, the poles of which are 27 and 28, immediately below the lever 22, and if desired re- 45 spectively in alignment with the magnets 13 and 14. The electromagnet poles 27 and 28 are provided with, and energized, by means of fine wire coils 29 and 30, the terminals of which, 31 and 32, are respectively connected 50 with the positive side of the dynamo by means of the wire 20, and with the positive wire 4 of the battery, by means of the wire 32, and, therefore, constantly in circuit with the battery, through the field and armature 55 of the dynamo, so long as the switch is open, but are demagnetized by the closing of the switch, or by the current from the dynamo, when its voltage is at or above that of the battery. When the dynamo and battery volt- 60 age are equal the difference in voltage at terminals of this "holding" magnet is minimum and, therefore, is excited at a minimum when the dynamo and train are in motion, and maximum when the train is at rest. 65 This being the case, the magnetic attraction

of the locking magnet serves to hold the switch in an open position when the train stops, against its being accidentally closed by the jars from a rough track, sudden coupling up or stoppage, nor by physical contact by 70 the operator or others which would otherwise move the lever to contact with its lifting and retaining magnet. Further, when the voltage of the battery is below normal, the attraction of the lifting coils 18 exceeds 75 the attraction of the holding coils 29 and 30 sooner, and later, when the voltage of the battery is high, with the result that the holding magnet serves as a compensating device causing the switch to be closed sooner 80 or later respectively when the voltage of the battery is low or high. It should here be observed that the current through this holding magnet divides between the dynamo armature and the field a larger portion of 85 this current passes through the field, when the commutator and brushes are loose or gummed, than when clean, so that this current serves to excite the field more strongly at this time, and a voltage is generated high 90 enough to break down and maintain so, the high resistance due to gummy commutators, and thereby insure the dynamo's "picking up" immediately when set in motion.

With the immediate operation of the dynamo when put in motion, there is avoided the loss of available current due to delay in starting the dynamo, and the preventing of excessive current when the switch closes at a high train speed and when the automatic 100 regulator of the system is unable to act fast enough to avoid a heavy rush of current, the blowing of fuses and shock to the whole system including the battery.

In conclusion, it should be observed that 105 my invention is not limited to its use between a storage battery and a dynamo for it is equally well adapted for use in connection with a gravitating contact switch connection between two dynamos or other 110 sources or receivers of current. Nor is my invention limited to its use in connection with switch contacts operated by a gravitating lever and magnet as distinguished from any other form of movable member com- 115 monly employed for moving a switch to and maintaining it in a closed position.

Having described my invention, what I claim and desire to secure by Letters Patent is:

1. An automatically operated switch system comprising in combination, a dynamo, a storage battery, a switch device, a movable support for the contacts thereof, an electro-magnet for holding the switch in its 125 open position, in series circuit with the dynamo and storage battery.

2. An automatically operated switch comprising in combination switch contacts, means for making and breaking connection 130

between said contacts, and an electromagnet for holding the switch in open position connected across the contact posts of the switch and deenergized by the contact fingers when switch is in closed position.

3. An automatically operated switch comprising in combination, switch contact posts and contact fingers, means for making and breaking connection between said contact posts, and contact fingers, and an electromagnet for holding the switch in open posi-

tion, connected across the contact posts and shunted and deenergized by the contact fingers when switch is in closed position.

In witness whereof, I have hereunto set 15 my hand and affixed my seal this 26th day of June, A. D. 1912.
